BURNS DICK, OF ST. LOUIS, MISSOURI, ASSIGNOR TO WAGNER ELECTRIC CORPORATION, OF ST. LOUIS, MISSOURI, A CORPORATION OF DELAWARE.

IGNITION MECHANISM.

Application filed May 25, 1923. Serial No. 641,342.

This invention relates to ignition mechanism for internal combustion engines and particularly to a combined timer and distributor unit having the characteristics and advantages hereinafter pointed out.

In ignition apparatus now in use for multi-cylinder engines the circuit breaker or "timer" is either in the same compartment with the distributor and enclosed by the same cover or casing, or otherwise so located with respect to other operative parts that neither access to it nor inspection of its operation is possible while the engine is running. This condition makes it impossible to ascertain whether faulty operation of an ignition system is due in whole or in part to the timer or timer contacts, and necessitates trial of various adjustments until a satisfactory one is found if possible. Since the actual operation of the timer cannot be observed, unnecessary inspections and adjustments of it are often made in an attempt to locate and overcome the cause of improper engine operation when such cause may not be in the timer or even in any part of the ignition system.

One of the objects of my invention is to provide a combined timer-distributor unit in which the operation of the timer may be readily observed while the engine is running and consequently at varying engine speeds. Another object is to reduce the breaker arm inertia to a very low point whereby operation at the higher engine speeds is improved. Other objects and advantages will appear from the following more detailed description.

In the accompanying drawings Figure 1 is a side view, partly in elevation and partly in section, of a timer-distributor mechanism embodying my invention; Figure 2 is a horizontal cross-section on the line 2—2 of Figure 1; Figure 3 is a side view showing breaker arm and associated parts (the cover therefor being removed); and Figure 4 is a plan view of the spark advance lever shown in side view in Figure 1.

The main support for the timer-distributor mechanism is the casting 1 having its lower end cylindrical for insertion in the standard S. A. E. mounting, in which it enters the mounting sleeve on the generator (not shown). The operating shaft 2 extending through this support is provided at the lower end with the standard coupling

3, and at its upper end carries the distributor 4. This shaft also carries the cam 6 keyed thereto in the form shown, but may be integral with it.

The support 1 is provided with a longitudinally extending slot 7 having its inner opening opposite the cam. The breaker arm 8 is pivotally mounted on hub 5 on the exterior of the support 1 and extends over the exterior opening of the slot 7. Seated in this slot 7, and freely movable longitudinally therein, is a strip of fiber or other suitable material 9, which is not connected to the breaker arm but by means of which the cam imparts impulses to this arm. The outer end of the arm carries contact 10 cooperating with adjustable contact 11 connected to contact terminal 12, both 11 and 12 being insulated from the support 1. Spring 19 returns the breaker arm to closed position. A removable covering cap or casing 13, which may be held in place by the spring bail 14, or other suitable means, encloses the timer lever and contacts.

The contact terminals 22 of the distributor mechanism are carried in the insulating cap or head 15 in the usual manner and this cap is removably secured to the support 1 by means of screws 16. Condenser 18 is mounted on the support 1 and has one terminal connected to terminal 12 and the other to the support. 21 indicates the opening for lubricating the drive-shaft.

It will be understood from the drawings that the high tension circuit comprises the central terminal of the cap 15, the conductive portions of distributor arm and the outer terminals of the cap in succession. The low tension circuit comprises the support, the contacts 10 and 11, and the terminal 12.

The lever 17, whose inner end is clamped around the support 1, is connected to the manual spark control lever (not shown) and serves to rotate the support 1 in the mounting sleeve and thus adjusts the time of spark occurrence with respect to engine piston position. The clamping mechanism, by means of which the lever 17, is connected to the support 1, renders it easy to make the proper initial adjustment of the lever with respect to this support after the mechanism has been assembled on the engine. The lever is a one piece stamping, the part embracing the support being flexible and having a

free end connected by bolt 20 to the body of the lever.

In the operation of the mechanism the fiber strip 9 is actuated by the cam 6 and alternately separates and permits reengagement of the circuit breaker contacts 10 and 11, and it will be noted that the location of contacts and breaker pivot at points removed from cam construction permits the 10 use of a very short breaker arm and this reduces its necessary weight and consequently its inertia whereby the time of separation of contacts at high speed is reduced.

Since the fiber strip 9 is not attached to 15 the breaker arm, the weight of rivets or other attaching means heretofore employed is omitted and the breaker arm can be placed at considerable distance from the cam and thus rendered easily visible without adding 20 weight to the moving breaker parts, since the weight of the added length of fiber is compensated for by omission of means for attaching it to the arm. The long bearing of the fiber in the slot 7 in the support also 25 makes it possible to employ a thin and consequently light strip of fiber.

The cover 13 on the breaker mechanism may be removed without disturbing the 30 operative parts of that mechanism or of the distributor and the character and regularity of the breaker action can be observed and even contact adjustments be made while the engine is running. This constitutes a marked advantage over timer-distributor 35 structures in which tedious "cut and try" methods of locating and removing causes of faulty ignition are necessary.

Having fully described my invention,

what I claim as new and desire to secure by Letters Patent of the United States is: 40

1. An ignition unit for an internal combustion engine, comprising a support, a cam rotatable therein, a spring actuated circuit breaker arm mounted on the support, and a breaker actuating member freely slidable in 45 either direction in the wall of the support and held in operative relation with the cam by the breaker arm.

2. An ignition unit for an internal combustion engine, comprising a support, a 50 drive shaft extending therethrough, a cam on said shaft, said support having an inner wall portion closely adjacent to the periphery of the cam, a distributor arm actuated by the shaft, a circuit breaker mechanism 55 mounted on the exterior of the support, and a breaker actuating member adapted to convey impulses from the cam to the breaker mechanism, said actuating member extending through and wholly supported by the 60 wall of the support.

3. An ignition unit for an internal combustion engine, comprising a support, a rotatable cam within the support, a circuit breaker mechanism mounted on the exterior 65 of the support and comprising a movable arm carrying a contact, and a breaker arm actuating member freely slidable in either direction in an opening through the wall of the support and adapted to engage the 70 breaker arm to convey impulses from the cam to said arm but not attached to either.

In testimony whereof, I have hereunto set my hand and affixed my seal.

BURNS DICK. [L. S.]
